(57) **CLAIM**

The ornamental design for a paper towel dispenser, as shown and described.

DESCRIPTION

FIG. 1 is a top, front perspective view of a paper towel dispenser in accordance with a first embodiment of our new design, shown in a closed position;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a top, front perspective view of a paper towel dispenser in accordance with a second embodiment of our new design, shown in an open position;

FIG. 9 is a front elevation view thereof;

FIG. 10 is a rear elevation view thereof;

FIG. 11 is a left side elevation view thereof;

FIG. 12 is a right side elevation view thereof;

FIG. 13 is a top plan view thereof; and,

FIG. 14 is a bottom plan view thereof.

The oblique shade lines in FIGS. 1-2 show a transparent surface and not surface ornamentation.

The broken lines depict unclaimed subject matter and form no part of the claimed design.

The dot-dash lines in FIGS. 1-2 and 6 represent the boundary between the claimed and unclaimed portions of the design and form no part of the claim.
